UNITED STATES PATENT OFFICE.

LAWRENCE RICHARDSON, OF LOUISVILLE, KENTUCKY.

BOLSTER CONSTRUCTION.

Application filed November 26, 1924. Serial No. 752,304.

This invention relates to bolster constructions.

In freight car constructions now in use, derailments caused by excessive rocking of the car body are not uncommon.

Accordingly, one object of the invention is to provide simple and efficient means for preventing excessive rocking of cars and derailment thereof.

10 Another object is to provide a simple, durable and practicable bolster construction for limiting rocking action of cars and maintaining sufficient weight on the wheels on the high rail to prevent derailments.

15 These and other objects are accomplished by means of the arrangement disclosed by the accompanying sheet of drawings, in which.

Figure 1 is a fragmentary side elevation 20 of a railway car embodying my invention, and

Figure 2 is a sectional view taken transversely of the car and longitudinally through the spring bolster member.

25 The various novel features of the invention will be apparent from the following description and drawings and will be particularly set forth in the appended claims.

Referring to the figures of the drawings, it 30 will be noted that the invention is illustrated in connection with a railway car having a body 10 with a body bolster 11 having a center bearing 12 engaging the center bearing portion of a second bolster member 13,

35 the latter of which is mounted within and supported by a third bolster member 14. The bolster member 11 has side bearings 15 which are adapted to engage side bearings 16 on the intermediate bolster member 13. The

40 truck bolster member 14 preferably is hollow and has a depressed floor portion 17 with flat bearing portions 18 which receive and support the intermediate bolster member 13.

45 The points of support 18 fall within the "A" lines connecting the center of gravity 19 of the car and the heads of the rails 20 so that under conditions which would cause violent rocking of the car, such rocking ac-

50 tion would take place about such points 18 within said "A" lines whereby a certain minimum weight will be maintained on the outside or light wheels, or wheels on the high rail, making it practically impossible for a

55 wheel to become derailed. It will be appreciated that if the points of support 18 should

be outside of the "A" lines in question that derailments would be more apt to occur. Also preferably the points of support 18 of one bolster member with respect to the other 60 should be located as low with respect to the rails as possible. In this way said points may be spaced an increased amount and still be within the "A" lines thereby lessening the chance of any rocking action upon said points 65 of support. The side bearing members 15 and 16 correspond to the regular side bearings and they are located far enough out from the center so that they can be easily inspected and maintained. As a result there- 70

of, clearance between said side bearings may be easily watched and maintained so that just the proper clearance will be permitted and no more to minimize the rocking action 75 permitted between said side bearings 15 and 16. Placing of the side bearings 15 and 16 out a considerable distance also minimizes the maximum load to be sustained by said bearings. This is particularly important 80 in connection with heavy cars as the main- 85 tenance of side bearings on such cars has been a difficult problem. By means of the supporting arrangement between the two bolster members 13 and 14 it is possible to place the points of contact in a low plane 90 with respect to the rail as mentioned hereinbefore, thereby making the distance between said points of support a maximum and lessening the chance of rocking on said points.

In this connection it will be noted that the bolster member 14 is supported upon springs 21 which in turn rest upon the tension member 22 of side frames 23.

The three bolster members 11, 13 and 14 95 are all transverse bolster members and are in vertical alignment. The bolster member 11 is the usual body bolster member, and the bolster members 13 and 14 may be called the truck or spring bolster members. It will 100

be noted that two of the three bolster members have cooperative side bearings and one of the three bolster members supports another one of said bolster members within itself at two spaced points inside the lines connecting the center of gravity of the car and the heads of the rails, normally to prevent rocking of one of said bolster members upon the other to minimize the rocking of the car. In this connection, let it be assumed 105 that the left hand upper side bearing mem- 110 ber 15 has passed or rocked into engagement

with the associated side bearing member 16. This rocking pressure is thereby transmitted to the intermediate bolster 13 through a relatively small lever arm represented by the 5 horizontal distance between the vertical lines passing through bearings 16 and 18. The total pressure of the car body is distributed throughout the full length of the intermediate bolster 13 and accordingly throughout 10 the bolster 14 and by virtue of the fact that the bearing points 18 are low and relatively close to the wheels, relatively great pressure is maintained on the high wheels which under the imposed conditions are at the right 15 side of the truck. Accordingly excessive rocking action and derailments are avoided or at least minimized.

It will be understood that the parts may be arranged in various different combinations 20 and it is my intention to cover all such arrangements and modifications which do not involve a departure from the spirit and scope of the invention.

I claim:

25 1. In a railway car, the combination of a body bolster having side bearings, and a truck bolster comprising two bolster members one within the other and one of said bolster members supporting the other at two spaced points inside the lines connecting the center of gravity of the car and the heads of the rails normally to prevent rocking of one of said bolster members with respect to the other and to minimize rocking of the car, 30 one of said bolster members having side bearings for cooperative engagement with said other bearings.

2. In a railway car, the combination of a body bolster having side bearings, and a truck bolster comprising two bolster members, one of said bolster members supporting the other at a plurality of spaced points in a relatively low plane with respect to the rails and inside of the lines connecting the 40 center of gravity of the car and the heads of the rails normally to prevent rocking of one of said bolster members with respect to the other and to minimize rocking of the car; one of said bolster members having side 45 bearings for cooperative engagement with said other bearings.

50 3. In a railway car, the combination of a body bolster having side bearings, a spring bolster member having a plurality of spaced points of support, and an intermediate bolster member mounted within said second bolster member and upon said spaced points of support normally to prevent rocking of said intermediate bolster member upon the spring bolster member and to minimize rocking of the car.

60 4. In a railway car, the combination of a

body bolster, a spring bolster member having a plurality of spaced points of support, and an intermediate bolster member having 65 side bearings cooperating with said other side bearings and mounted within said spring bolster member and upon said spaced points of support normally to prevent rocking of said intermediate bolster member upon the 70 spring bolster member and to minimize rocking of the car.

5. In a railway car, the combination of three bolster members, two of which have cooperative side bearings and one of the three 75 of which supports another at two spaced points inside of the lines connecting the center of gravity of the car and the heads of the rails to minimize rocking of the car.

6. In a railway car, the combination of 80 three bolster members, two of which have cooperative side bearings and one of the three of which supports another within itself and at two spaced points inside of the lines connecting the center of gravity of the car and the heads of the rails to minimize rocking of the car.

7. In a railway car, the combination of three parallel arranged vertically aligned bolster members, two of which have cooperative side bearings, and one of the three of which supports another one at two spaced points inside of the lines connecting the center of gravity of the car and the heads of the rails to minimize rocking of the car. 95

8. In a railway car, the combination of three bolster members two of which have a cooperative association with respect to each other and one of the three of which supports another one within itself and at two spaced 100 points inside of the lines connecting the center of gravity of the car and the heads of the rails to minimize rocking of the car.

9. In a railway car, the combination of three parallel arranged vertically aligned bolster members, two of which have cooperative side bearings outside the lines connecting the center of gravity of the car and the heads of the rails, and one of the three of which bolsters supports another one at two 105 spaced points inside of said lines to minimize rocking of the car.

10. In a railway car, the combination of three bolster members, two of which may have cooperative side bearings, and one of the three of which supports another one at two spaced points inside of the lines connecting the center of gravity of the car and the heads of the rails to minimize rocking of the car. 115
